(57) **CLAIM**

The ornamental design for an automobile hood ornament, as shown and described.

DESCRIPTION

FIG. 1 is a right-side elevation view of the first embodiment of an automobile hood ornament showing the illuminated region in an illuminated state, showing my new design, a left-side elevation view being a mirror image that is claimed but not shown;

FIG. 2 is a rear view thereof;

FIG. 3 is a top plan view thereof;

FIG. 4 is a front elevation view thereof;

FIG. 5 is a front right perspective view thereof; and

FIG. 6 is a front left perspective view thereof.

FIG. 7 is a right-side elevation view of the second embodiment of an automobile hood ornament a left-side elevation view being a mirror image that is claimed but not shown;

FIG. 8 is a rear view thereof;

FIG. 9 is a top plan view thereof;

FIG. 10 is a front elevation view thereof;

FIG. 11 is a front right perspective view thereof; and,

FIG. 12 is a front left perspective view thereof.

The broken lines in the figures illustrate portions of the automobile hood ornament and form no part of the claimed design.
